UNITED STATES PATENT OFFICE

129,162

DESIGN FOR A BOTTLE OR SIMILAR ARTICLE

David Fischman, Great Neck, N. Y.

Application June 12, 1941, Serial No. 101,420

Term of patent 7 years

To all whom it may concern:

Be it known that David Fischman, a citizen of the United States and resident of Great Neck, in the county of Nassau, State of New York, has invented a new, original, and ornamental Design for a Bottle or Similar Article, of which the following is a specification, reference being had to the accompanying drawing, forming part thereof, and in which,

Fig. 1 is a front perspective view of a bottle, embodying my new design;

Fig. 2 is an end perspective view thereof; and
Fig. 3 is a top plan view thereof.

I claim:

The ornamental design for a bottle or similar article, substantially as shown.

DAVID FISCHMAN.
